UNITED STATES PATENT OFFICE.

LINCOLN JOHNSON, OF MARBLE, COLORADO.

RAIL-TIE.

1,072,236.

Specification of Letters Patent.

Patented Sept. 2, 1913.

Application filed May 29, 1913. Serial No. 770,769.

To all whom it may concern:

Be it known that I, LINCOLN JOHNSON, a citizen of the United States, and a resident of Marble, in the county of Gunnison and State of Colorado, have made certain new and useful Improvements in Rail-Ties, of which the following is a specification.

My invention relates to improvements in rail ties and it consists in the combinations, 10 constructions, and arrangements herein described and claimed.

An object of my invention is to provide a tie which forms a positive bond between the two rails, and which prevents the spreading 15 of the rails.

A further object of my invention is to provide a rail tie constructed largely of metal, but which is provided with a cushion block to absorb the shocks from the impact of the 20 loads coming on the rail.

Other objects and advantages will appear in the following specification and the novel features of the device will be particularly pointed out in the appended claims.

25 My invention is illustrated in the accompanying drawings forming part of this application in which similar reference characters indicate like parts in the several views and in which—

30 Figure 1 is a perspective view of the tie, Fig. 2 is a longitudinal sectional view therethrough, Fig. 3 is a plan view, Fig. 4 is a perspective view of one of the cushion blocks, and Fig. 5 is a perspective view of 35 one of the rail clips.

In carrying out my invention I provide a channel-shaped base plate 1 like that shown in Fig. 1. The upper edges of the ends of the base plate 1 are cut away as shown at 1^x. 40 On each of the sides of the base plate are elongated slots or openings 2 arranged to receive wedges 3 and 4. These wedges, as will be seen from the drawings, are inclined in opposite directions. Secured to the upper 45 edges of the base plates are clips such as that shown in Fig. 5. These consist each of a body portion 6 having a slot 6^a arranged to receive the upper edge of the base plate.

The body portion 6 is provided with openings 6^b for the reception of rivets or bolts by means of which the clip may be secured to the base plate. The body portion 6 is provided with an extension 6^c which is arranged to engage the base 7 of the rail. 50

55 From the bottom portion of the base plate 1 flanges 8 are struck up. These flanges

form abutment members for the cushion blocks 9, such as that shown in Fig. 4. The latter are preferably made of any suitable wood. In practice the blocks may be used 60 as they come from the tree, or they may be treated with any suitable wood preservative to lengthen the life of the block. These blocks are provided with cut-away portions 9^x at their inner corners in order to allow 65 room for the clips 6.

The chairs for the rails comprise body portions 10 having side flanges 10^x which are bent downwardly and then inwardly as shown at 10^y being arranged to enter underneath and to engage flanges 11 which are struck outwardly from the base members 1. The body portions 10 have secured to their upper surfaces a rail brace 12 of the shape shown in the drawings. On the opposite 75 side of the rail from the rail braces the body portions are extended as shown at 10^a, one side 10^b of the extension being inclined. The ends of these extensions terminate in loops 10^c which are formed by bending the end 80 back upon itself and securing it in the manner shown in Fig. 2. In order to clamp the cushion block 9 securely in position I provide the downwardly extending flanges 13, which are stamped from the body portions 85 10 of the chair seats.

From the foregoing description of the various parts of the device the operation thereof may be readily understood. The chairs are placed in position with the inclined edges 90 10^b on the opposed chairs facing in opposite directions, as shown in Fig. 3. The wedges 3 and 4 are passed through the loops and are driven home, thereby drawing the brace members 12 firmly against the outer side of 95 the rails and forcing the bases 7 of the rails tightly against the clips. The extensions 6^a of the clips prevent any movement of the rail. In order to prevent any movement of the wedges after the device is in position 100 cotter pins are passed downwardly through the openings 10^d which are arranged to register with openings 3^x and 4^x in the wedges 3 and 4 respectively. A number of the latter openings are provided so that in any position of the wedges the openings 10^d will 105 register with some one of the openings in the wedge.

A tie constructed according to this invention holds the rails securely and prevents 110 spreading. No spikes or other rail fastening means are necessary. The rail rests upon a

metal chair and therefore does not wear the cushion block as it would if the base on the rail came directly into contact with the block. The life of the cushion block is therefore increased.

By using clips of varying size to hold the inside of the base of the rail it is possible to vary the gage of the track within the limits required on curves. In this case it will be necessary to use a slightly larger cushion block.

It will be noted that the flanges 11 have a slight downward slope toward the center of the base to engage the flange 10 which has a similar slope. Now when the wedges are tightened the chair seat is firmly drawn to the cushion block.

I claim:

1. A rail tie comprising a metal base portion, a cushion block carried by said base portion near each end thereof, a rail chair supported upon each of said cushion blocks, abutment members carried by the base for engaging the inner edges of the rails, a brace member carried by each of said rail chairs for engaging the outer sides of the rails, means for drawing the rail chairs together, said last named means comprising an extension carried by each rail chair and directed toward the other extension, the ends of the extensions having alined openings, and wedges arranged to enter said openings for drawing the extensions inwardly.

2. A rail tie comprising a metal base portion, a cushion block carried by said base portion near each end thereof, a rail chair supported upon each of said cushion blocks, abutment members carried by the base for engaging the inner edges each of the rails, a brace member carried by each of said rail chairs for engaging the outer sides of the rails, means for drawing the rail chairs together, said last named means comprising an extension carried by each rail chair and directed toward the other extension, the ends of the extensions being bent back upon themselves to form elongated loops, and wedges having surfaces inclined in opposite directions arranged to enter said loops for drawing the extensions inwardly.

3. A rail tie comprising a metal base portion, a cushion block carried by said base portion near each end thereof, a rail chair supported upon each of said cushion blocks, abutment members carried by the base for engaging the inner edges of the rails, a brace member carried by each of said rail chairs for engaging the outer sides of the rails, means for drawing the rail chairs together, said last named means comprising

an extension carried by each rail chair and directed toward the other extension, the ends of the extensions being bent back upon themselves to form elongated loops, wedges having surfaces inclined in opposite directions arranged to enter said loops for drawing the extensions inwardly, and means for locking the wedges in position.

4. A rail tie comprising a base plate of U-shaped cross section, the sides of the base plate being provided with elongated slots, clips carried by the upper edges of the sides of said base plates and arranged to hold the inner edges of the base of the rail, a cushion block disposed between the sides of said base plate near each end of said plate, a rail chair carried by each of said cushion blocks, braces carried by said chairs and arranged to engage the outer side of the rails, integral flanges carried by said rail chairs and arranged to engage portions of said base plate, each of said rail chairs having an extension directed toward the other chair, the ends of the extensions being provided with openings arranged to register with the slots in the sides of the base, and wedges adapted to enter the alined slots and openings for drawing the rail chairs together.

5. A rail tie comprising a base plate of U-shaped cross section, the sides of the base plate being provided with elongated slots, clips carried by the upper edges of the sides of said base plates and arranged to hold the inner edges of the base of the rail, a cushion block disposed between the sides of said base plate near each end of said plate, a rail chair carried by each of said cushion blocks, braces carried by said chairs and arranged to engage the outer side of the rails, integral flanges carried by said rail chairs and arranged to engage portions of said base plate, each of said rail chairs having an extension directed toward the other chair, the ends of the extensions being provided with openings arranged to register with the slots in the sides of the base, and wedges adapted to enter the alined slots and openings for drawing the rail chairs together, means for preventing the movement of the cushion blocks, said means comprising flanges carried by the base and arranged to bear on the inner sides of the block, and opposing flanges carried by the rail chairs and arranged to bear on the outer sides of the blocks.

LINCOLN JOHNSON.
